MINING MACHINE

Charles A. Pratt, Chicago, Ill., assignor to Goodman Manufacturing Company, Chicago, Ill., a corporation of Illinois

Application January 3, 1933, Serial No. 649,805

20 Claims. (Cl. 262—28)

This invention relates to improvements in mining machines of the track mounted type capable of cutting horizontal kerfs in the mine wall adjacent the mine bottom in front of and to each side of the track, or at various elevations and planes with respect thereto including a kerf adjacent the mine roof while the machine is held in a stationary position on the track together with shearing kerfs at either side of the longitudinal center line of the machine, and has as its general objects to provide a new and improved machine of the class described constructed with a view towards general all around efficiency, ruggedness, compactness, and ease and simplicity of operation.

A track mounted mining machine of a type similar to that disclosed in my present invention is disclosed in a prior application filed November 23, 1931, Serial No. 576,635, which issued as Patent No. 1,979,050, on October 30, 1934, so the present disclosure will be directed more particularly to the improved features calculated to improve the efficiency of the machine and permit the cutting of shearing kerfs and kerfs adjacent the mine roof, as well as along the mine bottom.

Other objects of my invention will appear from time to time as the following specification proceeds.

My invention may be more clearly understood with reference to the accompanying drawings wherein:

Figure 1 is a top plan view of one embodiment of my invention;

Figure 2 is an enlarged partial fragmentary side elevation of the forward portion of the device shown in Figure 1 with parts broken away and taken in longitudinal section;

Figure 3 is an enlarged partial fragmentary side elevation of the rearward portion of the embodiment of my invention illustrated in Figure 1, with parts broken away and taken in longitudinal section;

Figure 4 is an enlarged partial fragmentary plan view of the forward portion of the embodiment of my invention illustrated in Figure 1, with parts broken away and in section to more clearly show the details thereof;

Figure 5 is a sectional view taken substantially along line 5—5 of Figure 2;

Figure 6 is a sectional view taken substantially along line 6—6 of Figure 4; and

Figures 7, 8, and 9 are partial diagrammatic views showing various operating positions of the

embodiment of my invention illustrated in Figure 1.

Like reference characters refer to like parts throughout the various figures.

Referring now in particular to the embodiment of my invention illustrated in the accompanying drawings, a truck 10 is provided which comprises a truck frame 11 mounted on track wheels 12 and axles 13. A pivotally movable frame 14 is supported on the truck frame 11 for pivotal movement with respect thereto about a boss 15 extending upwardly from the rearward end of said truck frame and disposed on the longitudinal center line thereof.

Cutting mechanism, generally indicated by reference character 16, is supported on the pivotally movable frame 14 in a manner which will hereinafter be more fully described. Said cutting mechanism includes a motor 17 disposed adjacent the rearward end thereof, a housing 18 disposed forwardly of said motor and providing a bearing support and housing for a portion of the gearing for driving a cutter chain 21 about a cutter bar 20 and feeding said cutter bar in the coal in the manner fully described in my aforementioned prior application. The housing 18 also has bearing support means formed integral therewith for supporting a forwardly extending cutter frame 19, whereby said cutter frame may be adjusted about an axis extending longitudinally of said housing and held in various positions of adjustment with respect thereto during the cutting operation. The cutter frame 19 extends forwardly of the pivotally movable frame 14 and truck 10 and provides a support 35 for the cutter bar 20. The cutter bar 20 has the cutter chain 21 movable thereabout in a closed orbital path in the usual manner and said cutter bar is supported by the cutter frame 19 for adjustment with respect thereto in a plurality of 40 parallel planes and for pivotal movement about an axis disposed perpendicularly to the axis of pivotal movement of said cutter frame.

A pair of trunnion supports 23 are disposed adjacent the forward end of the pivotally movable frame 14 on each side of the cutting mechanism 16 for supporting said cutting mechanism for pivotal movement about an axis extending transversely thereof and for adjusting the angle of the cutter bar 20 with respect to the mine bottom to enable said cutter bar to cut where the bottom or coal seam is uneven.

The cutting mechanism 16 is yieldably supported and moved about its axis of pivotal connection to the trunnion supports 23, 23 in a usual

manner by means of suitable yieldable adjusting means disposed adjacent its rearward end and generally indicated by reference character 24.

The drive for the truck 10 includes an armature pinion 25 disposed on the rearward end of an armature shaft 26 for the motor 17. The armature pinion 25 meshes with and drives a spur gear 27 keyed to a sleeve 28 having a sun gear 29 cut integral therewith. The sun gear 29 forms 5 a driving element for a planetary gear reduction device, generally indicated by reference character 30, which is of a usual construction so will not herein be described in detail. The planetary gear reduction device 30 is controlled by a suitable 10 friction band 31 in the usual manner and is provided with low speed clutch jaws 32 adapted to be meshed with clutch jaws 33 formed integral with a clutch sleeve 34 for driving a longitudinally extending shaft 35 at a low frictionally controlled 15 speed. Likewise, clutch jaws 36 are formed integral with the inner end of the sleeve 28 and are adapted to be meshed with the clutch jaws 33 for driving the longitudinally extending shaft 35 at a higher speed. Said longitudinally extending shaft is connected with a transversely extending shaft 37 disposed beneath the truck frame 11 by means of a suitable worm and worm gear drive 38, splined shaft 39 slidably engaged with the worm gear of said worm and worm gear 20 drive, a bevel gear 40 driven by the lower end of said splined shaft, and bevel gears 41 driven thereby and selectively connectible with the transversely extending shaft 37 by means of suitable clutch mechanism in the usual manner (not 25 shown) so that said shaft may be driven in one direction when connected with one of the bevel gears 41 and in an opposite direction when connected with said opposite bevel gear. The transversely extending shaft 37 is connected 30 to the rearward truck axles 13 for driving said truck axles by means of a suitable chain and sprocket drive, generally indicated by reference character 42, and the forward and rearward truck axles are connected together by means of a suitable chain and sprocket drive, generally indicated by reference character 43. Thus the truck 10 35 may move about the mine on its own power at either a high speed or a low frictionally controlled speed in either a forward or reverse direction without reversal of the motor 17. This provides a means for speedily moving the mining machine about the mine and positioning said machine for cutting with ample power for propelling the mining machine at a relatively slow feeding speed 40 for feeding the cutter bar 20 into the coal, particularly when cutting shearing kerfs in the mine wall and for propelling the mining machine where the track is rough or the grades are relatively steep. An arcuate rack 44 extends upwardly from the forward end of the truck frame 11 and its teeth face towards the rearward end of the mining machine. Said rack is formed on a radius whose center is coaxial with the axis of pivotal connection of the pivotally movable frame 14 to the truck frame 11. Said rack is meshed with a pinion 45 carried on the lower end of a vertical shaft 46 and journaled on its hub in the lower portion of the housing 18. The pinion 45 is driven from the motor 17 at either a high or low frictionally controlled speed in reverse directions without reversal of said motor for pivotally moving the pivotally movable frame 14 by means of a suitable system of gears which will hereinafter be more 50 fully described.

The forward end of the pivotally movable frame 14 is supported on suitable rollers 47 which ride in an arcuate shaped channeled guideway 49, which guideway in turn is slidably supported in the truck frame 11 for supporting said pivotally movable frame when its forward end is beyond the boundaries of said truck frame in a manner which has been fully described in my aforementioned prior application. The rearward portion of the pivotally movable frame 14 is supported on suitable rollers 50 which ride in an arcuate shaped channeled guideway 51 disposed rearwardly of the rearward truck axles but forwardly of the boss 15. 5

A counterweight 52 is provided on the rearward end of the pivotally movable frame 14 to counteract the weight of the cutter frame 19 and cutter bar 20. Said counterweight is disposed rearwardly of the truck frame 11 and depends from the rearward portion of the pivotally movable 10 frame 14.

Referring now in particular to several of the novel features of my invention and the means for supporting the cutter frame 19 by the housing 18 for pivotal movement about an axis extending longitudinally of the cutting mechanism 16, said cutter frame is provided with a rearwardly extending neck 53 which is carried in the housing 18 for rotation with respect thereto by a suitable bearing support, the lower half of which is formed integral with said housing. A bearing member 54 is spaced forwardly of the neck 53 and is integral with the cutter frame 19. Said bearing member is of a larger diameter than the neck 53, but its longitudinal center is coaxial with the axis of rotation of said neck. Said bearing member is journaled in a suitable bearing support, the lower half of which is integral with the housing 18 and extends forwardly of the truck frame 11. A cap piece 55 forms the upper half of the bearing support for the neck 53 and bearing member 54 and extends upwardly from the housing 18 and is detachably secured thereto by suitable cap screws in an ordinary manner. A split annular retaining ring 57 is secured to the forward end of the cap piece 55 and bearing formed integral with the housing 18 by means of suitable cap screws and a portion of its inner surface abuts a shouldered portion 58 on the forward side of the bearing member 54. 20

Suitable means are provided for rotating the cutter frame 19 with respect to the cutting mechanism 16 which include a spur gear 59 freely mounted on the neck 53 forwardly of its portion which is journaled in the housing 18. A suitable clutch member 60 is feathered on the neck 53 and is provided with rearwardly facing clutch jaws 61 which are adapted to mesh with forwardly facing clutch jaws 63 formed integral with the forward side of a spur gear 64 disposed forwardly of and formed integral with the spur gear 59. The spur gear 64 serves as a drive member for pivotally moving the cutter bar 20 and adjusting said cutter bar with respect to the cutter frame 19, in a manner which will hereinafter be more 30 fully described. A suitable reversible frictionally controlled plural speed drive connection is provided from the motor 17 to the spur gear 59 for driving said spur gear at either a high or low frictionally controlled speed in reverse directions without reversal of said motor, which drive connection will be more fully described as this specification proceeds. Thus, when the spur gear 59 is connected with the motor 17 so as to be driven therefrom and the clutch jaws 61 are meshed with 35

the clutch jaws 63, the cutter frame 19 is pivotally moved with respect to the housing 18 in an obvious manner.

Suitable means are provided for locking the cutter frame 19 in various fixed positions with respect to the housing 18, which means may be of any construction but is herein preferably shown as being a pin and aperture lock comprising a threaded pin 65 carried in a projecting lug 10 66 integral with the cutter frame 19. Said threaded pin is carried in said lug for free translational movement with respect thereto but held from rotational movement in a suitable manner (not shown) and is adapted to register with any one 15 of a plurality of spaced apertures 67 formed in the split annular ring 57 and forward face of the cap piece 55 and forward end of the portion of the housing 18 forming a bearing support for the bearing member 54. A suitable hand wheel 68 is threaded on the pin 65 and abuts the forward side of the projecting lug 66 and is provided with a grooved hub 69, the grooved portion of which is engaged by a holding member 70 so rotation 20 of said hand wheel will engage the pin 65 with or disengage said pin from the desired aperture 67.

With reference now in particular to the means for supporting the cutter bar 20 for movement towards and away from the cutter frame 19, a pair of parallel spaced guides 73 disposed forwardly of the bearing member 54 extend outwardly from opposite sides of said cutter frame in a plane perpendicular to a plane intersecting and parallel with the axis of rotation of said cutter frame. The parallel spaced guides 73 are adapted to be engaged by corresponding parallel spaced guides 74 extending upwardly from an annular support member 75.

A portion 72 of the annular support member 75 extends therefrom and has a member 77 trunnioned therein which carries a threaded shaft 76. Said threaded shaft extends upwardly from the member 77 and is threaded within a hub 79 of a worm gear 80 journaled in the cutter frame 19 adjacent the forward end thereof in a suitable manner. Said threaded shaft is held from translational movement with respect to the member 77 by means of a pinion 78 keyed on its outer end and abutting the outer side of the member 77 and a suitable shouldered portion abutting 50 the opposite end of said member. The annular support member 75 forms an annular bearing member for a cutter bar support member 81 to which the cutter bar 20 is secured in a usual manner. The cutter bar support member 81 is held from translational movement with respect to said annular support member by means of an annular ring 82 secured to said cutter bar support member in a suitable manner and abutting a shouldered portion formed in said annular support member. An internal rack 83 is secured to the upper side of the cutter bar support member 81 adjacent the forward end thereof. Said rack is adapted to be meshed with the pinion 78 so that rotation of said pinion will pivotally move 55 the cutter bar support member 81 and cutter bar 20 about an axis perpendicular to the axis of rotation of the cutter frame 19.

Suitable means are provided for rotating the worm gear 80 and translationally moving the threaded shaft 76 with respect to the cutter frame 19 or for rotating said shaft and pivoting the cutter bar 20 about an axis disposed perpendicularly to the axis of rotation of said cutter frame. Said means, as herein shown, comprise a shaft 84 70 extending longitudinally of the cutter frame 19

and journaled therein. Said shaft has a pinion 85 keyed on its rearward end, which pinion is meshed with and driven from the spur gear 64 formed integral with the spur gear 59. The axis of rotation of the longitudinally extending shaft 84 is so arranged with respect to the axis of rotation of the cutter frame 19 that the pinion 85 may ride around the spur gear 64 as the cutter frame 19 is in various positions of adjustment with respect to the housing 18 so that said shaft 10 may be driven from said spur gear in all positions of adjustment of said cutter frame with respect to said housing. A worm 87 is freely mounted on the shaft 84 adjacent its forward end and is journaled in and encased in a suitable worm 15 and worm gear housing formed integral with the forward portion of the cutter frame 19. Suitable clutch jaws 88 are formed integral with and extend rearwardly from the hub of the worm 87 and are adapted to be engaged by suitable clutch 20 jaws 89 formed integral with and extending forwardly of a clutch member 90 feathered on the shaft 84. The clutch member 90 is shifted by means of a suitable system of links and levers in a usual manner (not shown) for selectively driving the worm 87 from the shaft 84. It is thus apparent that when the worm gear 80 is driven from the worm 87, that the threaded shaft 76 will move translationally with respect to the cutter frame 19 for adjusting the position of the 30 cutter bar 20 with respect to said cutter frame.

Suitable clutch jaws 91 are formed integral with and extend upwardly from the upper side of the worm gear 80 and are adapted to be engaged by suitable clutch jaws 92 depending from a clutch member 93 feathered on the threaded shaft 76 in a suitable manner so that when the clutch jaws 92 engage the clutch jaws 91, said threaded shaft will be rotated by the worm gear 80 which in turn will drive the pinion 78 and pivot the cutter bar 20 about an axis disposed perpendicularly of the axis of rotation of the cutter frame 19. The worm 87 and worm gear 80 are of the self-locking type; that is, the pitch of said worm and worm gear is such that said worm gear cannot drive said worm. Thus the threaded shaft 76 is held from rotation when the worm 87 is disconnected from the shaft 84 and the cutter bar 20 is locked in various angular positions with respect to the cutter frame 19.

Referring now in particular to the means for driving the cutter chain 21 about the cutter bar 20 and the drive mechanism for pivoting the pivotally movable frame 14 and effecting rotational movement of the cutter frame 19 about 55 an axis disposed longitudinally of the cutting mechanism 16, pivotal movement of the cutter bar 20 about an axis disposed perpendicularly to the axis of rotation of said cutter frame and adjustment of said cutter bar towards or away from said cutter frame, an armature pinion 94 is provided on the forward end of the armature shaft 26. Said armature pinion meshes with a spur gear 95 keyed on the rearward end of a longitudinally extending shaft 96 journaled in the housing 18 and neck 53 of the cutter frame 19 for rotation about an axis coaxial with the axis of rotation of said cutter frame. A bevel pinion 97 is keyed on the forward end of the longitudinally extending shaft 96 and meshes 60 with and drives a bevel gear 98 journaled on its hub within the cutter frame 19 in the usual manner. A cutter chain drive sprocket 99 is adapted to mesh with and drive the cutter chain 21 and is keyed adjacent the lower end of a sleeve mem- 75

ber 100 journaled in the support member 81 for rotation about an axis coaxial with the axis of pivotal movement of the cutter bar 20. The bevel gear 98 and sprocket 99 are operatively connected together so said sprocket may be driven by said bevel gear in all positions of adjustment of the cutter bar 20 with respect to said bevel gear by means of a suitable splined shaft 101 in a usual manner.

10 A pinion 103 is keyed on the longitudinally extending shaft 96 forwardly of the rearward bearing support for said shaft and meshes with and drives a spur gear 104 keyed adjacent the rearward end of a longitudinally extending shaft 105 disposed beneath the longitudinally extending shaft 96. The longitudinally extending shaft 105 is journaled in suitable bearing supports extending upwardly from the housing 18 and has a spur gear 107 keyed thereto adjacent its rearward portion but forwardly of the pinion 103. The spur gear 107 meshes with and drives spur gears 108 and 109 disposed on opposite sides thereof. A spur gear 110 is keyed on the forward end of the longitudinally extending shaft 105 and meshes with and drives idler pinions 111 and 112, which idler pinions in turn mesh with and drive spur gears 113 and 114, respectively, disposed on opposite sides of the longitudinally extending shaft 105 and coaxial with the axis of rotation of the spur gears 107 and 108. The spur gear 108 is thus driven from the longitudinally extending shaft 105 in a direction opposite to which the spur gear 113 is driven from said shaft and the spur gear 109 is driven from said shaft in an opposite direction to which the spur gear 114 is driven from said shaft.

15 The spur gears 108 and 113 are keyed on the hubs of suitable friction clutch members 115 and 116, respectively, which clutch members are in turn freely mounted on a sleeve 117. Said sleeve is freely mounted on a longitudinally extending shaft 118 journaled in suitable bearing supports extending upwardly from the bottom portion of the housing 18. A suitable clutch member 119, having oppositely disposed friction engaging faces 120, 120, is feathered on the sleeve 117 so that when one face 120 engages the friction engaging face of the clutch member 115, the sleeve 117 will be driven in one direction and when the opposite face 120 engages the friction engaging surface of the clutch member 116, the sleeve 117 will be driven in an opposite direction. The clutch members 115, 116 and 119 may be of any construction well known to those skilled in the art but are herein preferably shown as being of a friction cone type.

20 A sun gear 121 is formed integral with the forward end of the sleeve 117 and forms a driving gear for a planetary gear reduction device 122 controlled by a suitable friction band 123 in a usual manner. Said planetary gear reduction device is provided with high speed clutch jaws 124 and low speed clutch jaws 125 which are adapted to be engaged by clutch jaws 126 on a sliding clutch member 127 feathered on the longitudinally extending shaft 118 for driving said shaft at either a high or low frictionally controlled speed. A spur pinion 129 is keyed on the forward end of the longitudinally extending shaft 118 and meshes with and drives the spur gear 59 journaled on the neck 53.

25 It is thus apparent that the spur gear 59 may be driven from the motor 17 at either a high or low frictionally controlled speed in reverse directions without reversal of said motor. Thus, when

30 the spur gear 59 is driven from the motor 17 and the clutch jaws 61 are engaged with the clutch jaws 63, the cutter frame 19 may be rotated about an axis extending longitudinally of the cutting mechanism 16 at either a high or low frictionally controlled speed and the direction of rotation of said cutter frame may be reversed without reversal of the motor. Thus, an improved positioning means has been provided for rotatably adjusting the cutter frame 19 and cutter bar 20 10 for cutting either adjacent the mine bottom or mine roof or at various angles with respect to the mine bottom and mine roof. It is further apparent that when the clutch jaws 61 are disconnected from the clutch jaws 63, the spur gear 59, while acting as a means for rotatably adjusting the cutter frame 19, also acts as a common drive member for pivoting the cutter bar 20 about an axis disposed perpendicularly to the axis of rotation of the cutter frame 19 at either a high or low frictionally controlled speed without reversal of the motor 17 or for moving said cutter bar towards or away from said cutter frame.

35 The pinion 45, meshing with the arcuate rack 44, is driven from the motor 17 at either a high or low frictionally controlled speed without reversal of said motor for pivotally moving the pivotally movable frame 14 across the truck frame 11 in opposite directions by means of either of the spur gears 109 or 114 through a friction clutch member 130 adapted to engage either a friction clutch member 131 on which the spur gear 109 is secured or a friction clutch member 132 on which the spur gear 114 is secured for driving a frictionally controlled planetary gear reduction device 133 in opposite directions without reversal of the motor 17 in an obvious manner. A longitudinally extending shaft 135 is driven from the frictionally controlled planetary gear reduction device 133 at either a high or low frictionally controlled speed in the same manner that the longitudinally extending shaft 118 is driven from the planetary gear reduction device 122. A bevel pinion 136 is keyed on the forward end of the longitudinally extending shaft 135 and meshes with and drives a bevel gear 137 on the upper end of a vertical shaft 138. A spur gear 139 is secured to the vertical shaft 138 beneath the bevel gear 137 and meshes with and drives a spur gear 140 keyed on the vertical shaft 46 on the opposite side of the housing 18 from the pinion 45.

40 With reference now to Figures 7, 8 and 9 diagrammatically showing several cutting positions of the devices embodying my invention, the machine is adapted to be held in a stationary position during the cutting operation by means of suitable jack sockets 141 detachably connected to the outer ends of the rearward truck axles 13 and adapted to engage the mine rail and mine bottom which have suitable jacks 142, 142 interposed therebetween and the mine roof or mine wall. Figures 7 and 9 show the cutter bar 20 positioned for shearing to either side of the longitudinal axis of the cutting mechanism 16. In shearing, the cutter bar 20 is usually positioned so its forward end is adjacent the mine roof. The cutter chain 21 is then put in operation and the entire machine is moved forwardly along the track at a relatively slow feeding speed controlled by the frictionally controlled planetary gear reduction device 30 until the cutter bar 20 has been moved into the coal to the desired depth. The machine may then be held in a stationary position on the track by means of the

45

50

55

60

65

70

75

5 jack sockets 141, 141 and jacks 142, 142 and the cutter bar 20 may be pivotally moved about an axis disposed perpendicularly to the axis of pivotal movement of the cutter frame 19 until the forward end of said cutter bar is adjacent the mine bottom. When in such a position, the jacks 142, 142 and jack sockets 141, 141 are removed and the machine is moved rearwardly along the track withdrawing the cutter bar 20 therefrom.

10 In Figure 7, the cutter bar 20 is shown by dotted lines as positioned for cutting adjacent the mine bottom while in Figure 8 said cutter bar is shown by solid lines as cutting adjacent the mine roof. Cuts adjacent the mine roof or mine bottom may be made in a manner which has been fully disclosed in my aforementioned prior application and which will accordingly not herein be described in detail.

15 While I have herein shown and described one form in which my invention may be embodied, I do not wish to limit myself to the precise construction and arrangement of parts shown, it being understood that alterations or changes may be made without departing from the spirit and 20 scope thereof. Furthermore, I do not wish to be construed as limiting myself to the particular embodiment illustrated, excepting as it may be limited in the appended claims.

25 I claim as my invention:

30 1. In a mining machine of the class described, a support, a pivotally movable frame supported on said support for movement about a vertical axis disposed adjacent the rearward end thereof, a motor on said pivotally movable frame and means driven by said motor for pivotally moving said pivotally movable frame, including a rack on the forward end of said support, having a pinion meshing therewith, cutting mechanism supported on said pivotally movable frame including a cutter frame extending beyond the forward boundaries of said support and carried for rotation about an axis extending longitudinally of said cutting mechanism and a cutter bar pivotally movable about an axis disposed perpendicularly to the axis of rotation of said cutter frame and means driven by said motor for rotating said cutter frame or pivotally moving said cutter bar when said cutter frame is in various positions of adjustment with respect to said support including a pair of coaxial gears rotatable about an axis coaxial with the axis of pivotal movement of said cutter frame.

35 2. In a mining machine of the class described, a support, a pivotally movable frame supported on said support for movement about a vertical axis disposed adjacent the rearward end thereof, cutting mechanism supported on said pivotally movable frame including a cutter frame extending beyond the forward boundaries of said support and carried for rotation about an axis extending longitudinally of said cutting mechanism and a cutter bar pivotally movable about an axis disposed perpendicularly to the axis of rotation of said cutter frame, locking means for positively holding said cutter frame in various positions of adjustment with respect to said support and drive gearing coaxial with the axis of rotation of said cutter frame for selectively rotating said cutter frame or pivotally moving said cutter bar about its axis of pivotal connection to said cutter frame including a gear having selective connection with said cutter head and another gear coaxial therewith and driven thereby having selective connection with said cutter bar for

40 swinging said cutter bar in a plane parallel to the axis of pivotal movement of said cutter frame.

45 3. In a mining machine of the class described, a support, a pivotally movable frame supported on said support for movement about a vertical axis disposed adjacent the rearward end thereof, cutting mechanism supported on said pivotally movable frame including a cutter frame extending beyond the forward boundaries of said support and carried for rotation about an axis extending longitudinally of said cutting mechanism and a cutter bar pivotally movable about an axis disposed perpendicularly to the axis of rotation of said cutter frame, a pin and aperture locking device for holding said cutter frame in various 50 positions of adjustment with respect to said support and drive gearing coaxial with the axis of rotation of said cutter frame for selectively rotating said cutter bar about its axis of pivotal connection to said cutter frame including a gear having selective connection with said cutter head and another gear coaxial therewith and driven thereby having selective connection with said cutter bar for swinging said cutter bar in a plane parallel to the axis of pivotal movement of said cutter frame.

55 4. In a mining machine of the class described, cutting mechanism therefor including a cutter frame rotatable about a horizontal axis, a cutter bar supported thereby for pivotal movement about an axis disposed perpendicularly to the axis of pivotal movement of said cutter frame, and common drive means for selectively rotating said cutter frame or pivoting said cutter bar about its axis 60 of pivotal connection to said cutter frame comprising a drive gear coaxial with the axis of rotation of said cutter frame, a selective connection from said gear to said cutter head for rotating said cutter head therewith and another coaxial gear driven by said first mentioned gear and having driving connection with said cutter bar.

65 5. In a mining machine of the class described, cutting mechanism therefor including a cutter frame rotatable about a horizontal axis, a cutter bar supported thereby for pivotal movement about an axis disposed perpendicularly to the axis of pivotal movement of said cutter frame, and common drive means for selectively rotating said cutter frame or pivoting said cutter bar about its axis 70 of pivotal connection to said cutter frame comprising a drive gear coaxial with the axis of rotation of said cutter frame, a selective connection from said gear to said cutter head for rotating said cutter head therewith and another coaxial gear driven by said first mentioned gear and having driving connection with said cutter bar, and locking means for positively holding said cutter frame in various positions of adjustment with respect to said support comprising a pin and aperture lock.

75 6. In a mining machine of the class described, cutting mechanism therefor including a cutter frame rotatable about a horizontal axis, a cutter bar supported thereby for pivotal movement about an axis disposed perpendicularly to the axis of pivotal movement of said cutter frame, and common drive means for selectively rotating said cutter frame or pivoting said cutter bar about its axis of pivotal connection to said cutter frame comprising a drive gear coaxial with the axis of rotation of said cutter frame, a selective connection from said gear to said cutter head for rotating said cutter head therewith and another coaxial gear driven by said first mentioned gear and

- having driving connection with said cutter bar, locking means for positively holding said cutter frame in various positions of adjustment with respect to said support and other locking means for holding said cutter bar in various positions of adjustment with respect to said cutter frame.
7. In a mining machine of the class described, cutting mechanism therefor including a motor, a cutter frame disposed forwardly of said motor for rotation about a horizontal axis, a cutter bar supported thereby for pivotal movement about an axis disposed perpendicularly to the axis of pivotal movement of said cutter frame, and common drive means for selectively rotating said cutter frame or pivoting said cutter bar about its axis of pivotal connection to said cutter frame comprising a shaft extending longitudinally of said cutting mechanism driven by said motor and rotatable about an axis eccentric of the axis of rotation of said cutter frame, a gear coaxial with the axis of rotation of said cutter frame, a drive connection from said shaft to said gear, another gear rotated by and coaxial with said first-mentioned gear, a selective operative connection from said last-named gear to said cutter head and a selective drive connection from said last-named gear to said cutter bar.
8. In a mining machine of the class described, cutting mechanism therefor including a motor, a cutter frame disposed forwardly of said motor for rotation about a horizontal axis, a cutter bar supported thereby for pivotal movement about an axis disposed perpendicularly to the axis of pivotal movement of said cutter frame, and common drive means for selectively rotating said cutter frame or pivoting said cutter bar about its axis of pivotal connection to said cutter frame comprising a shaft extending longitudinally of said cutting mechanism driven by said motor and rotatable about an axis eccentric of the axis of rotation of said cutter frame, a gear coaxial with the axis of rotation of said cutter frame, a drive connection from said shaft to said gear, means for selectively connecting said gear with said cutter frame, another gear rotated by and coaxial with said first-mentioned gear, a selective operative connection from said last-named gear to said cutter head and a selective drive connection from said last-named gear to said cutter bar.
9. In a mining machine of the class described, cutting mechanism therefor including a motor, a cutter frame disposed forwardly of said motor for rotation about a horizontal axis, a cutter bar supported thereby for pivotal movement about an axis disposed perpendicularly to the axis of pivotal movement of said cutter frame, and common drive means for selectively rotating said cutter frame or pivoting said cutter bar about its axis of pivotal connection to said cutter frame comprising a shaft extending longitudinally of said cutting mechanism driven by said motor and rotatable about an axis eccentric of the axis of rotation of said cutter frame, a gear coaxial with the axis of rotation of said cutter frame, a drive connection from said shaft to said gear, a drive connection from said gear to said cutter bar for pivoting said cutter bar and a selective connection from said gear to said cutter frame for rotating said cutter frame upon rotation of said gear and at the same speed as the speed of rotation of said gear.
10. In a mining machine of the class described, cutting mechanism therefor including a motor, a cutter frame disposed forwardly of said motor for rotation about a horizontal axis, a cutter bar supported thereby for pivotal movement about an axis disposed perpendicularly to the axis of pivotal movement of said cutter frame, and common drive means for selectively rotating said cutter frame or pivoting said cutter bar about its axis of pivotal connection to said cutter frame comprising a shaft extending longitudinally of said cutting mechanism driven by said motor and rotatable about an axis eccentric of the axis of rotation of said cutter frame, a gear coaxial with the axis of rotation of said cutter frame, a drive connection from said shaft to said gear, another gear coaxial with said first-mentioned gear, a selective operative connection from said last-named gear to said cutter frame, a gear driven by said last-named gear and a drive connection from said driven gear to said cutter bar.
11. In a mining machine of the class described, cutting mechanism therefor including a motor, a cutter frame disposed forwardly of said motor for rotation about a horizontal axis, a cutter bar supported thereby for pivotal movement about an axis disposed perpendicularly to the axis of pivotal movement of said cutter frame, and common drive means for selectively rotating said cutter frame or pivoting said cutter bar about its axis of pivotal connection to said cutter frame comprising a shaft extending longitudinally of said cutting mechanism and disposed eccentrically of the axis of rotation of said cutter frame, a gear coaxial with the axis of rotation of said cutter frame, a drive connection from said motor to said shaft including plural speed gear reduction mechanism, a drive connection from said shaft to said gear, another gear coaxial with said first-mentioned gear, a selective operative connection from said last-named gear to said cutter frame, a gear driven by said last-named gear and a drive connection from said driven gear to said cutter bar.
12. In a track mounted mining machine, a truck, a pivotally movable frame thereon, cutting mechanism supported on said pivotally movable frame including a motor, a cutter frame disposed forwardly of said motor for rotation about an axis disposed longitudinally of said cutter frame, a cutter bar supported by said cutter frame for pivotal movement about an axis disposed perpendicularly to said axis of pivotal movement of said cutter frame, and other means driven by said motor for pivotally moving said pivotally movable frame and other means driven by said motor for independently rotating said cutter frame or pivotally moving said cutter bar comprising a common drive member coaxial with the axis of pivotal movement of said cutter frame, a selective connection from said gear to said cutter frame including a clutch member and another drive connection from said gear to said cutter bar.
13. In a track mounted mining machine, a truck, a pivotally movable frame thereon, cutting mechanism supported on said pivotally movable frame including a motor, a cutter frame disposed forwardly of said motor for rotation about an axis disposed longitudinally of said cutter frame, a cutter bar supported by said cutter frame for pivotal movement about an axis disposed perpendicularly to said axis of pivotal movement of said cutter frame, a drive connection from said motor for pivotally moving said pivotally movable frame in reverse directions without reversal of said motor including reverse gearing, and an

other drive connection from said motor independent of said first mentioned drive connection for rotating said cutter frame or pivotally moving said cutter bar comprising a common drive member and reverse gearing interposed between said motor and drive member.

14. In a track mounted mining machine, a truck, a pivotally movable frame thereon, cutting mechanism supported on said pivotally movable frame including a motor, a cutter frame disposed forwardly of said motor for rotation about an axis disposed longitudinally of said cutter frame, a cutter bar supported by said cutter frame for pivotal movement about an axis disposed perpendicular to said axis of pivotal movement of said cutter frame, a drive connection from said motor for pivotally moving said pivotally movable frame at a plurality of frictionally controlled speeds including a frictionally controlled geared reduction device, and another drive connection from said motor independent of said first mentioned drive connection for rotating said cutter frame or pivotally moving said cutter bar at a plurality of frictionally controlled speeds comprising a common drive member and a frictionally controlled plural speed geared reduction device interposed between said motor and drive member.

15. In a track mounted mining machine, a truck, a pivotally movable frame thereon, cutting mechanism supported on said pivotally movable frame including a motor, a cutter frame disposed forwardly of said motor for rotation about an axis disposed longitudinally of said cutter frame, a cutter bar supported by said cutter frame for pivotal movement about an axis disposed perpendicular to said axis of pivotal movement of said cutter frame, a drive connection from said motor for pivotally moving said pivotally movable frame at a plurality of frictionally controlled speeds in reverse directions without reversal of said motor including reverse gearing and a frictionally controlled geared reduction device, and another drive connection from said motor independent of said first mentioned drive connection for rotating said cutter frame or pivotally moving said cutter bar at a plurality of frictionally controlled speeds in reverse directions, without reversal of said motor comprising a common drive member, and reverse gearing and a frictionally controlled plural speed geared reduction device interposed between said motor and drive member.

16. In a mining machine, a support, a frame on said support swingable with respect thereto about a vertical axis disposed adjacent the rearward end of said support, a motor on said frame, means driven by said motor for horizontally swinging said frame including a rack on the forward end of said support and a pinion meshing therewith, cutting mechanism on said frame including a cutter frame rotatable about an axis extending longitudinally thereof, a cutter bar swingable about an axis perpendicular to the axis of rotation of said cutter frame, a cutter chain movable about said cutter bar, means for driving said cutter chain about said cutter bar including a shaft rotatable about an axis parallel to the axis of rotation of said motor and coaxial with the axis of rotation of said cutter frame and means driven by said motor for rotating said cutter frame, including a shaft eccentric of the axis of rotation of said cutter frame and having a geared drive connection with drive

means coaxial with the axis of rotation of said cutter head.

17. In a mining machine, a support, a frame on said support swingable with respect thereto about a vertical axis disposed adjacent the rearward end of said support, a motor on said frame, means driven by said motor for horizontally swinging said frame including a rack on the forward end of said support and a pinion meshing therewith, cutting mechanism on said frame including a cutter frame rotatable about an axis extending longitudinally thereof, a cutter bar swingable about an axis perpendicular to the axis of rotation of said cutter frame, a cutter chain movable about said cutter bar, means for driving said cutter chain about said cutter bar including a shaft rotatable about an axis parallel to the axis of rotation of said motor and coaxial with the axis of rotation of said cutter frame, and means driven by said motor for rotating said cutter frame and independently swinging said cutter bar including a shaft parallel to and eccentric of the axis of rotation of said cutter frame and having a geared drive connection with drive means coaxial with the axis of rotation of said cutter frame.

18. In a mining machine, a support, cutting mechanism on said support including a motor, a cutter frame rotatable about a longitudinal axis, a cutter bar carried by said cutter frame for pivotal movement about an axis perpendicular to the axis of pivotal movement of said cutter frame, said cutter bar having a cutter chain movable thereabout, means driven by said motor for driving said cutter chain about said cutter bar including a shaft rotatable about an axis parallel to the axis of rotation of said motor and coaxial with the axis of rotation of said cutter head, and means driven by said motor for rotating said cutter frame including a shaft parallel to but eccentric of the axis of rotation of said cutter frame, a gear coaxial with the axis of rotation of said cutter frame driven by said shaft and a selective connection between said gear and cutter frame.

19. In a mining machine, a support, cutting mechanism on said support including a motor, a cutter frame rotatable about a longitudinal axis, a cutter bar carried by said cutter frame for pivotal movement about an axis perpendicular to the axis of pivotal movement of said cutter frame, said cutter bar having a cutter chain movable thereabout, means driven by said motor for driving said cutter chain about said cutter bar including a shaft rotatable about an axis parallel to the axis of rotation of said motor and coaxial with the axis of rotation of said cutter head, and means driven by said motor for rotating said cutter frame and independently swinging said cutter bar about an axis perpendicular to the axis of rotation of said cutter head including a shaft parallel to but eccentric of the axis of rotation of said cutter frame, a selective connection from said gear to said cutter frame, and a drive connection from said gear to said cutter bar for swinging said cutter bar.

20. In a mining machine, a support, cutting mechanism on said support including a motor, a cutter frame rotatable about a longitudinal axis, a cutter bar carried by said cutter frame for pivotal movement about an axis perpendicular to the axis of pivotal movement of said cutter frame, said cutter bar having a cutter chain movable thereabout, means driven by said motor for driving said cutter chain about said cutter

bar including a shaft rotatable about an axis parallel to the axis of rotation of said motor and coaxial with the axis of rotation of said cutter head; and means driven by said motor for rotating said cutter frame and independently swinging said cutter bar about an axis perpendicular to the axis of rotation of said cutter head including a shaft parallel to but eccentric of the

axis of rotation of said cutter frame, a gear coaxial with the axis of rotation of said cutter frame and driven by said eccentric shaft, a selective connection from said gear to said cutter frame; a coaxial gear driven from said first mentioned gear and a drive connection from said gear to said cutter bar.

CHARLES A. PRATT.
